CARPENTER HAND PLANE

Lawrence C. Lumetta and Samuel S. Lumetta,
Detroit, Mich.

Application July 28, 1949, Serial No. 107,214

3 Claims. (Cl. 145—5)

1

This invention relates to surfacing planes and in particular to improvements in hand planes for carpenters.

Carpenter planes have been employed heretofore over a long period to remove small areas or amounts of wood or other material. However, the several devices of the prior art have not proven entirely satisfactory inasmuch as they are complicated in design and construction, expensive to manufacture, difficult to properly adjust for use, and clog easily.

With the foregoing in view, the primary object of the invention is to provide a plane which is simple in design and construction, inexpensive to manufacture, easy to properly adjust for use, and which will not clog.

An object of the invention is to provide a plane of a minimum number of parts, namely, three parts: a body, a blade, and a set screw.

An object of the invention is to provide a plane capable of cutting coextensively with the sides of the plane body.

An object of the invention is to provide a plane capable of cutting any easily adjusted distance sidewise outwardly beyond either side of the plane body.

An object of the invention is to provide a plane capable of cutting sidewise inwardly a regulatable and variable distance inside either of the sides of the plane body.

An object of the invention is to provide a plane equipped with a blade capable of adjustment for cutting in either direction of plane movement by either a pushing or pulling action.

An object of the invention is to provide a blade easily settable as to depth of cut which is positively easily securable in the adjusted position.

An object of the invention is to provide a blade positioned a comparatively large distance away from the leading surface of the plane with the space being large enough to permit the ready displacement of shavings so that the shavings cannot clog the cutting area of the blade or become lodged between the leading plane surface and the blade.

These and other objects of the invention will become apparent by reference to the following description of a carpenter's plane embodying the invention taken in connection with the accompanying drawing in which:

Fig. 1 is a side elevational view of a plane embodying the invention.

Fig. 2 is a top plan view of the plane of Fig. 1.

Fig. 3 is a cross-sectional view of Fig. 1 taken on the line 3—3 thereof.

2

Fig. 4 is a cross-sectional view of Fig. 1 taken on the line 4—4 thereof.

Fig. 5 is a partial view similar to Fig. 2 showing the blade in adjusted position extending sidewise outwardly of the plane; and

Fig. 6 is a perspective view of the blade.

Referring now to the drawing wherein like numerals refer to like and corresponding parts throughout the several views, the carpenter's plane disclosed therein to illustrate the invention comprises a plane body 10 equipped with an integral blade receiving housing or chamber 11 interrupted or slotted by the work contacting surface 12 of the body 10 as a chord to form an opening in the work contacting surface 12 to permit the protrusion of the cutting edge of a blade below the surface 12, an imperforate arcuate blade 14 rotatably nesting in the housing or chamber 11 so as to be capable of projecting its cutting edge below the surface 12, a threaded aperture 15 in the body 10, and a set-screw 16 threaded in the aperture 15 and adapted to exert force on the blade 14 so as to wedge the blade 14 between the set-screw 16 and the body 10 to secure the blade 14 in adjusted position relative to the body 10.

More particularly, the body 10 comprises a one-piece metal casting with integral hand-grips including a rear platen 20 and a front platen 21 spaced apart by a space 22 so as to provide an open area for the protrusion of a blade's cutting edge therebetween, a bridge 23 rigidly uniting the platens 20 and 21 having a cylindrical interior chamber 11 completely open at either side of the bridge 23 with the chamber 11 communicating with the space 22, and a threaded aperture 15 at the top of the bridge 23.

The blade 14 comprises an arcuate, imperforate member 14 having cutting edges 24 and 25 ground thereon sidewise slidably insertable into the chamber 11 with the blade 14 being nearly circumferentially co-extensive with the walls of the bridge 23 defining the chamber 11 with the blade 14 being rotatable in either direction relative to the body 10 to position either the cutting edge 24 or the cutting edge 25 in cutting position so that the cutting direction can be either forward or rearward with a pushing or drawing action respectively and with the blade 14 being laterally positionable relative to the body 10 at points at, within, or beyond the lateral extent of the body 10.

The set screw 16 comprises a threaded portion 26 threadable in the threaded aperture 15 of the body 10 and a knurled hand portion 27 facilitat-

ing manual tightening and loosening of the end of the set screw 16 against the blade 14; tightening the set screw 16 against the blade 14 reacts on the body 10 at the top of the bridge 23 and exerts downward force on the blade 14 which is transmitted to areas of the blade 14 adjacent the cutting edges 24 and 25 with the transmitted force being resisted by the adjacent areas of the bridge 23 and/or platens 20 and 21 thereby placing the blade 14 in pressure contact with the body 10 immediately adjacent the cutting edges 24 and 25 thereof. This not only secures the blade 14 but also prevents vibration of the blade or "chattering" in use. As seen in the drawing, especially Figs. 2 and 5, the action of the set screw 16 is the same regardless of the relative lateral position of the blade 14 to the body 10.

In operation, the user sets the blade 14 as to extent of protrusion of either cutting edge 24 or 25 below the surface 12 and as to relative lateral position to the body 10 and then tightens the set screw 16. The plane is then ready for use. No adjusting thumb screws are required nor blade straightening levers as in the devices of the prior art. The instant plane not only eliminates many parts but is actually superior in use especially for the amateur but it is also advantageous to the professional as he is not required to make multiple adjustments.

The general proportions and relationship of the platens, bridge, and blade indicated in the drawing and described herein are desirable to the proper functioning of the device but the front platen may be deleted and the bridge made to cantilever. Although the invention has been disclosed as a plane, obviously it may be used in a spoke-shave or draw-knife to form articles other than flat.

Although but a single embodiment of the invention has been shown and described in detail, it is obvious that many changes may be made in the size, shape, detail and arrangements of the various elements of the invention within the scope of the appended claims.

We claim:

1. A carpenter's plane comprising a body-housing having a blade-receiving chamber with cylindrical walls interrupted by the extended line of the work contacting surface of said body and a threaded aperture communicating with the cham-

ber; an arcuate substantially circular blade snugly and manually rotatably disposed in the chamber of said body so as to be adjustable to position the cutting edge of said blade below the work contacting surface of said body, and a set screw threaded in the body aperture abutting the outer surface of said blade to secure said blade relative to said body in adjusted position.

2. A carpenter's plane or its equivalent comprising a body having a blade receiving chamber defined by cylindrical walls, with said chamber opening through the work contacting surface of said body to permit the protrusion of a blade's cutting edge there-beyond, an arcuate blade disposed in said chamber being rotatably movable therein to graduate the amount of protrusion of said blade's cutting edge beyond said body's work contacting surface and sidewise slidably disposed to permit the sidewise adjustment of said blade's cutting edge, and a set screw adapted to urge said blade against said walls to prevent relative movement between said blade and said body in any adjusted position of said blade.

3. A carpenter's plane blade positioning and securing means comprising a blade receiving housing having cylindrical walls, an arcuate substantially co-extensive blade disposed in said housing, and a set screw threaded in said housing bearing on the outer surface of said blade to secure same against movement relative to said housing with the force exerted by said set screw being mainly resisted by said housing at two points substantially adjacent the cutting ends of said blade.
